ELECTROLYTIC REFINING OF IMPURE
ALUMINUMArthur F. Johnson, Cambridge, Mass., assignor to
Reynolds Metals Company, Richmond, Va., a
corporation of Delaware

Application January 3, 1946, Serial No. 638,831

3 Claims. (Cl. 204—67)

1

This invention relates to the refining of impure aluminum and has for its object the provision of an improved method and apparatus for the electrolytic production of aluminum from impure aluminum. My invention provides a simple and efficient method of converting impure aluminum, such as aluminum scrap, containing various alloying metals as impurities into pure aluminum and with the recovery of other metals from the impure aluminum. My invention is particularly concerned with the refining of molten impure aluminum and provides a method and apparatus for electrolytically depositing the pure aluminum on a cathode in a salt electrolyte fusion.

In accordance with my method, I provide in a salt fusion several separate bodies of molten impure aluminum, each in a retaining vessel advantageously having a porous diaphragm between the adjacent bodies, and pass an electric current through the fusion from one body to the other to electrolytically transport the aluminum through the diaphragms and deposit it on cathodes interposed between the bodies. I employ a temperature above the melting point of aluminum and the aluminum deposited on the cathodes coalesces in drops and falls to the bottoms of the vessels where it is accumulated for removal. In this embodiment of my aluminum refining method, I employ a number of separate refractory electrically non-conducting vessels for the bodies of impure molten aluminum which are pervious to the passage of aluminum ions. I pass the electric current through the several bodies of aluminum in the vessels in series and selectively separate the aluminum from the impurities which are retained in the vessels.

My invention also contemplates the provision of a scrap melting operation in combination with the electrolytic purification just described. Advantageously, I may subject scrap aluminum to a melting operation at a temperature resulting in a partial separation of impurities from the aluminum and pass the aluminum thus partly purified to the retaining vessels in the fusion for further purification.

My invention also comprises, in combination, a sloping hearth aluminum scrap melting furnace with means for effecting a partial separation of impurities from the aluminum, and means for

2

passing the partially purified aluminum into receiving vessels in the salt fusion of an electrolytic cell wherein pure aluminum is deposited in the fusion.

5 These and other novel features of the invention will be better understood after considering the following discussion taken in conjunction with the accompanying drawings, in which:

Fig. 1 is a plan view of electrolytic apparatus 10 embodying the invention;

Fig. 2 is a sectional view along line 2—2 of Fig. 1;

Fig. 3 is a sectional view along line 3—3 of Fig. 1;

15 Fig. 4 is a partial plan view of the cell of Fig. 1 with the cover removed;

Fig. 5 is a sectional side view of a modification of the cell of Fig. 1;

Fig. 6 is a view along line 6—6 of Fig. 5; and 20 Fig. 7 illustrates a combination of apparatus embodying the invention.

The embodiment of the invention illustrated in Figs. 1 to 4 comprises a supporting concrete structure 1 including a wall and a bottom in 25 which is placed a steel lining 2 to serve as a moisture and liquid barrier, and a layer of heat and electrically insulating material 3 such as rammed alumina. The inner lining 4 which is preferably formed of acid-proof bricks, such as red shale bricks, is in contact with the fused salt 30 electrolyte 5. The bath may be formed of any suitable halid material, such as a mixture of aluminum chloride and potassium chloride. I prefer to line the cell with vitreous dense bricks 35 which are substantially non-porous and insoluble in the fusion. I may coat the inner surface of the lining with an aluminum nitride refractory, such as described in my copending application

Serial No. 653,967, filed March 12, 1946, now Patent 2,480,475, dated August 30, 1949. The bottom of the cell receptacle for receiving the salt electrolyte slopes from both sides towards the center to the channel 6 which, in turn, slopes towards one side to a collecting sump 7 from which the 45 pure aluminum may be pumped out through the upright duct 8. As best shown in Figs. 2 and 3, two rows of bricks 10 and 11 project inwardly and provide supports for the series of deep narrow vessels 15 which are formed of porous refractory material, such as porous fused alumina. 50

These vessels are for receiving the separate bodies of impure aluminum to be purified and are held in proper spaced relation with respect to each other by the fused alumina spacers 16.

The removable cover assembly 20 comprises a flat metal plate 21 with three steel stiffening bars 22 attached thereto and several projecting arms 23 by means of which the cover assembly may be manipulated. The inside of the steel cover plate 21 is covered with a layer of insulating refractory 24, such as alumina, and the inner surface is covered with a layer of fire clay 25. The refractory lining is held in position by the angle member 26. Interposed between the horizontal flat surface of the angle member 26 and the upper surface of the layer of bricks 4 is a layer of asbestos packing 27 on which the entire cover assembly rests to effect the exclusion of air and its contained moisture from the inside of the cell and the loss of vaporized salt. Directly above each of the vessels 15, a hole 28 is formed through the cover and a short section of pipe 29 attached to the cover plate 21 extends upward a short distance and is covered with a removable cap 30. These holes, pipes and caps extend along the longitudinal center of the cell, as shown in Fig. 1, and provide a means for pouring molten impure aluminum into the porous vessels 15 from any suitable feed manifold having spouts insertable into the various holes.

A pair of identical graphite anodes 32 are connected to the current supply bars 33 which in turn connect to the power line 34. Each anode has a circuit clamp 35 attached to the bar 33 and also attached to an annular bracket 36 which is welded to the cover plate 21. A layer of electrical insulation 37 is interposed between the clamp 35 and bracket 36 to prevent current flowing into the cover plate. The inside of the clamp has an annular space for receiving the packing material 38, such as asbestos, which is held in gas sealing contact with the anodes by means of the gland member 39. The lower ends of the anodes are inserted into the first porous vessel of the series.

The identical graphite cathodes 41 are each mounted in a clamping means 42 similar to that which supports the anodes which are connected to the conducting bars 43 attached to the power line 44. The cathodes are suspended in the salt fusion close to one side of the last porous vessel of the series. Two thermocouples 45 and 46 for measuring the temperature of the fusion are inserted through the cover and into the fusion. The entire cover assembly comprising the refractory lining, the feed holes, anodes, cathodes and thermocouples is removable as a unit. The purpose of using two anodes and two cathodes is to get a better distribution of current through the series circuit.

The intermediate electrodes 50 are in the form of graphite slabs with a longitudinal cut by means of which they may be hung over the side of each porous vessel 15 with part of the graphite inserted into the bodies of molten aluminum 51 and part of the graphite in the salt fusion between the vessels.

In carrying out an operation of the invention in the apparatus of Figs. 1 to 4, the cell is heated and provided with the molten salt fusion 5. This fusion may be formed, for example, of a mixture of aluminum chloride 55% and potassium chloride 45%. The electrolyte is maintained at a temperature from the melting point of aluminum up to around 800° C. While various types of im-

pure aluminum may be treated, such as scrap aluminum or original aluminum to be upgraded, the invention is especially effective in the purification of scrap containing iron, silicon and copper. A typical example of scrap aluminum which may be treated successfully has the following composition:

	Percent
Si	.78
10 Fe	1.02
Cu	4.24
Mn	.45
Mg	.97
Cr	.11
15 Ni	.28
Ti	.06
Pb	.13
Zn	.26
Sn	.05
20 Al	Balance

The vessels 15 are filled with the impure molten aluminum through pouring spouts inserted through the holes 28 after removing the caps 29. During the operation, the filling holes are closed by the caps 30. An overall voltage between the anodes 32 and cathodes 41 of around 20 volts is satisfactory, giving approximately 2 volts between the intermediate electrodes when ten porous vessels are used. A cell of the type illustrated may be operated at a current density of around 2 amperes per square inch, especially when the cells are full of aluminum. The current density will, of course, vary as the metal level drops. During the operation, the aluminum ions are electrically transported through the porous walls of the vessels 15 and deposited as pure aluminum on that portion of the graphite intermediate electrodes suspended in the salt fusion. The metal coalesces in tiny droplets on the upright surfaces falling to the bottom of the cell and eventually flows into the channel 6 and the collecting sump 7. Periodically the cover is removed from the duct 8 and the pure aluminum is pumped out of the cell.

The metals usually present in scrap aluminum are so much lower in electromotive series that they are not transported through the porous fused alumina vessels 15 and accordingly remain in the vessels 15. These metals accumulate in the bottom and may be removed from time to time to prevent an undue accumulation. It will be apparent that these metallic impurities include several very valuable metals which are in easily recoverable form.

The modified form of cell illustrated in Figs. 5 and 6 is provided with anodes, cathodes and intermediate graphite electrodes similar to those illustrated in Figs. 1 to 3. The principal difference between the two cells is in the bottom construction and in the bottom shape of the porous fused alumina vessels.

The cell comprises a concrete exterior 60, a steel shell 61 serving as a barrier, rammed insulating refractory 62, and an inner layer of dense refractory brick, such as red shale brick 63. Each of the porous fused alumina vessels 64 has a sloping or V-shaped bottom. The sloping sides of the bottom rest on two rows of bricks 66 and 67 projecting from two opposite sides of the cell. The bricks forming the sloping surfaces 70 and 71 immediately beneath porous vessels are set very close, for example, around 1 inch or less from the bottoms of the vessels. The purpose of this narrow space is to provide the smallest possible channel for the flow of current in the fusion

under the porous vessels. The sloping surfaces 70 and 71 converge towards the channels 72 and 73 which in turn slope into the channel 74. The metal accordingly flows into the low end of channel 74 from which it may be pumped out by inserting a pump through duct 75.

The combination of apparatus illustrated in Fig. 7 comprises a sloping hearth scrap aluminum refining furnace 80 connected by conduit 81 to the electrolytic refining cell 82. The furnace has feed doors 83 and 84, preferably opening on a level with the sloping hearth 85 which slopes towards the metal receptacle or well 86. A rather large combustion space 87 is provided above the hearth and receptacle in which fuel is introduced through the burners 88. The fuel is preferably directed against an arched roof and the products of combustion pass through the stack 89. The molten aluminum runs from the hearth into the receptacle, and when the valve 90 is open, the metal flows through conduit 81 and down through the upright ducts 91 into the confining vessels 92 of the electrolytic cell. The electrolytic cell 82 is similar to that shown in Figs. 1 and 2.

In carrying out an operation in the combination of apparatus illustrated in Fig. 7, scrap aluminum, such as scrap containing some iron and copper, is thrown through the doors 83 and 84 onto the hearth 85. A temperature is used in the furnace such as to melt the aluminum without melting the iron and copper. The molten aluminum flows from the hearth 85 into the receptacle 86 and the metals which do not melt remain on the hearth. From time to time, these may be raked off the hearth through one of the doors 83 or 84.

That section of the conduit 81 immediately connected to the valve 90 is provided with an electrically heated jacket 93 which keeps the valve and duct thereunder at a temperature above the melting point of aluminum. At any time it is desired to replenish the metal in the vessels 92, the valve 90 may be opened to admit the proper amount of aluminum. The metal entering the electrolytic cell is in a semi-purified condition since much of the impurities were left in the sloping hearth furnace.

If desirable, several electrolytic cells may be connected to the sloping hearth furnace and the operation so carried out that the aluminum flows

more or less continuously into the electrolytic cells.

I claim:

- 5 1. In the electrolytic production of pure aluminum from impure aluminum, the improvement which comprises forming in an electrically non-conducting vessel, a molten salt fusion maintained at a temperature above the melting point of aluminum, confining in the fusion at least one body of molten impure aluminum, electrolytically transporting aluminum ions from the body of impure aluminum through a porous alumina vessel to a cathode and collecting molten aluminum thereon, said collected aluminum falling from the cathode to the bottom of the vessel, and leaving in the body of aluminum metals like manganese, iron and copper which are sufficiently below aluminum in the electromotive series that they are not transported through the porous alumina vessel to the cathode.

more or less continuously into the electrolytic cells.

I claim:

1. In the electrolytic production of pure aluminum from impure aluminum, the improvement which comprises forming in an electrically non-conducting vessel, a molten salt fusion maintained at a temperature above the melting point of aluminum, confining in the fusion at least one body of molten impure aluminum, electrolytically transporting aluminum ions from the body of impure aluminum through a porous alumina vessel to a cathode and collecting molten aluminum falling from the cathode to the bottom of the vessel, and leaving in the body of aluminum metals like manganese, iron and copper which are sufficiently below aluminum in the electromotive series that they are not transported through the porous alumina vessel to the cathode.
2. In the method of claim 1, using a salt fusion comprising aluminum chloride and another salt.
3. In the method of claim 1, providing in the salt fusion several porous alumina vessels each of which contains a body molten impure aluminum and transporting the aluminum ions from each body through the porous vessel to a separate cathode.

ARTHUR F. JOHNSON.
